UNITED STATES PATENT OFFICE.

JOHN H. VAN DEVENTER, OF BUFFALO, NEW YORK, ASSIGNOR TO BUFFALO FORGE COMPANY, OF BUFFALO, NEW YORK, A CORPORATION OF NEW YORK.

ROTARY ENGINE.

1,026,887.

Specification of Letters Patent.

Patented May 21, 1912.

Application filed May 15, 1911. Serial No. 627,166.

To all whom it may concern:

Be it known that I, JOHN HERBERT VAN DEVENTER, a citizen of the United States of America, residing at Buffalo, in the county of Erie and State of New York, have invented certain new and useful Improvements in Rotary Engines, of which the following is a full, clear, and exact description.

My invention relates to rotary engines and more particularly to engines with rotors each having a plurality of spirally disposed and intermeshing tooth blades.

Some of the objects of my invention have been to provide a rotary engine in which all end thrust on the shafts might be eliminated; also one in which there should be substantially no leakage of the fluid under pressure between ends of the rotors and the engine heads. To this end I employ two or more rotors each provided with one or more right hand and one or more left hand spirally arranged tooth blades and I place the admission ports between the intermeshing rotors and at the junction points of the right hand and left hand spirally arranged tooth blades; thus I accomplish the above objects and at the same time provide a very powerful rotary engine, which occupies a small space.

Another object has been to provide a rotary engine which should be very efficient in operation and economical in fluid consumption. In order to attain this object I have arranged the inlet port of my engine so that the fluid under its initial pressure is cut off from each bucket, as the rotors revolve, by the bucket which follows, or shortly after the time of admission of the fluid to said buckets. The fluid contained in each bucket after the supply has been cut off, continues to expand until each bucket has finished its cycle or until it is opened to the atmosphere, into which it is then exhausted.

By slight modification of the principal form shown and described in this application, I provide a reversible and also a multiple stage rotary engine which is very efficient and compact.

The above, together with many other advantages which will be apparent to those skilled in the art, have been accomplished by my invention herein shown and described.

In the specification and appended claims the term fluid will be used as a general term for the pressure medium but the engine is

especially adapted for the use of steam and obviously it is applicable to be driven with either steam or compressed air as well as any fluid under pressure.

Reference is to be had to the accompanying drawings, forming part of the specification, in which like characters of reference indicate like parts throughout the several views of which:

Figure 1 is a plan view of my engine. Fig. 2 is an end sectional elevation of the same taken on line A—B of Fig. 1. Fig. 3 is a bottom view of the engine with the rib broken away and shows the buckets as formed by the tooth blades on the rotors. Fig. 4 is a sectional end elevation and shows an inlet port of a modified shape. Fig. 5 is a diagrammatical view of a slightly modified form of my invention and shows a twin or two-stage effect. Fig. 6 is a diagrammatical sectional end view of the modified form shown in Fig. 5 and is taken on line C—D of that figure. Fig. 7 is a diagrammatical front elevation of a reversible engine. Fig. 8 is a diagrammatical plan view of the same. Fig. 9 is a diagrammatical sectional end view of the same and is taken on line E—F of Fig. 8.

In the drawings, (Figs. 1 to 3) 10 is the base of my engine which is provided with suitable bearings 11. Shafts 12 and 12^a are rotatably carried by the bearings 11 and the said shafts have mounted thereon, in a rigid manner, rotors 13 and 13^a respectively. Each rotor is provided with a plurality of right hand spirally disposed tooth blades 14 extending across the rotor for substantially one-half its length and a plurality of left hand spirally disposed tooth blades 15 extending across the rotor for substantially the remaining half of its length. The said right hand and left hand tooth blades meet and join one another at the center of each rotor. The right hand tooth blades 14 of one rotor are arranged to mesh with the left hand tooth blades 15 of the opposite rotor thus securing transmission of rotation and also forming buckets whereby the propulsion of the rotors is made possible.

Disposed beneath the rotors and preferably forming an integral part of the base 10 is a rib 16 (see Fig. 2) which preferably extends the full length of the rotors 13 and 13^a. This rib extends up in between the rotors to the point of intersection of the perimeters

of said rotors and is in conformity with said perimeters and in bearing contact therewith. The extent to which the rib envelops the said rotors depends upon the number of 5 tooth blades in each rotor and the angle which the said tooth blades make with the rotor shafts, it being necessary only that this rib extends around the rotors far enough to confine the fluid under pressure to any pair 10 of meshing tooth blades until the said pair of tooth blades cease to mesh or until the full capacity of each bucket formed by the intermeshing tooth blades, has been developed. Obviously if desired this rib may be continued 15 around the rotors and substantially surround them and thus form a casing in which the exhaust fluid may be confined and from which it may be carried to any desired place. 17 is the inlet port which is disposed 20 at the center of the length of the rib 16 and near its peak. This port is preferably disposed in a horizontal plane and extends from one side of the rib through to the opposite side so that the fluid entering under 25 pressure will be caused to impinge on both rotors at the same time. Suitable ports 18 and 19 are provided through which the fluid is conducted to the inlet port 17, the port 19 being provided at its outer end with a screw- 30 thread, whereby suitable piping may be connected thereto.

In Fig. 4 I have shown a modified inlet port 17^a. In this figure the upper wall of the port is shown concave thereby producing a turbine effect by causing the fluid to impinge upon the tooth blade at a tangent to the path of travel of said tooth blade.

In Figs. 5 to 9 I have shown in a diagrammatical manner a few of the many varied modifications of my invention. In Figs. 5 and 6, three rotors 20, 21 and 22 are disposed one above the other with their tooth blades intermeshing. These rotors are provided with shafts 23, 24 and 25 respectively. Two ribs, 26 and 27, are used and are placed on opposite sides of the engine; rib 26 being arranged between rotors 20 and 21, and rib 27 between rotors 21 and 22. Thus a twin effect or a two-stage effect 50 may be obtained by employing only three rotors instead of four and thereby making a very compact engine. The direction of rotation of these rotors is indicated by the arrows in Fig. 6. When arranged as a 55 twin engine the fluid under its initial pressure will be supplied to inlet ports of both ribs but when arranged as a two-stage engine the fluid under initial pressure may, for instance, be supplied to the inlet port of 60 the rib 26 and the inlet port of the rib 27 supplied with the exhaust from the rotors 20 and 21. Obviously, when used as a two-stage engine, as above described, the inlet ports carrying the fluid to the rotors 21 and 65 22 may be increased in length so as to com-

pensate for the decreased pressure of the fluid which is exhausted from the rotors 20 and 21. Furthermore by employing four rotors a triple effect may be produced.

In Figs. 7 to 9 a reversible engine is shown. In this modification two shafts 28 and 29 are employed and upon each is mounted a rotor 30 and 31 respectively. The blades of each of these rotors are preferably disposed in three alternately arranged positions, *i. e.*, the rotor 30 has two sections 32 and 33 which are provided with left hand spirally disposed tooth blades and one section 34 with right hand spirally disposed tooth blades, and the rotor 31 has two sections provided with right hand spirally disposed tooth blades 35 and 36 and one section provided with left hand spirally disposed tooth blades 37. These sections in the rotors are so arranged that the tooth 75 blades of one rotor mesh with those of the other rotor. Two ribs 38 and 39 are provided in this type of engine. The ribs are arranged one on each side of the rotors and preferably are each of such a length as to 80 only extend across the rotors for about two-thirds of their length. The rib 38 extends across the sections 32 and 34 of rotor 30 and sections 35 and 37 of rotor 31 while the rib 39 preferably extends across the sections 33 85 and 34 of rotor 30 and the sections 36 and 37 of rotor 31. When the fluid is forced through the inlet port in the rib 38 the rotors will revolve in the direction of the full line arrows, 40 and 41, but when the 90 fluid enters the inlet port in the rib 39 the rotors will then revolve in the direction of the dotted line arrows 42 and 43.

By referring to Fig. 3 it will clearly be seen that between the tooth blade 14 on the 105 rotor 13^a and the two tooth blades 45 and 46 on the rotor 13 between which the tooth blade 44 meshes, is formed a bucket 47. Each rotor being provided with a plurality of right hand and left hand spirally disposed tooth blades, the formation of but one double-sided bucket is started by the intermeshing tooth blades at any one time. At substantially the instant when such a bucket 110 is started during the revolution of the rotors, the fluid under pressure is made to impinge thereon, thus causing the capacity of said bucket to gradually increase on account of the recession of the points of mesh of the tooth blades forming the same toward the 115 ends of the rotors. When any such bucket is under pressure and the rotors are thereby revolved, the tooth blades forming one side of said bucket when passing the port cut off the supply of fluid from said bucket (see 120 Fig. 2), thus allowing the fluid contained in said bucket to expand until it has developed its full capacity or until the tooth blades forming said bucket cease to mesh. It is 125 evident that the ratio of expansion may be 130

changed by changing the size and location of the inlet port or the angle and length of the spirally disposed tooth blades.

By referring to Fig. 3, it will be seen that at the junction points of the right hand and left hand spiral tooth blades at the center of each rotor, angular pockets are formed and as the fluid under pressure is admitted at this point, any leakage at the end of the rotors is impossible. The only place where leakage may occur is between the perimeters of the rotors and the rib but as it is possible to make a very good and practically non-leaking contact at this point, there is very little leakage in my engine thus making it very efficient in operation.

Obviously some detailed modifications of my invention as herein shown and described may be made without departing from the spirit of my invention and I do not wish to be limited to the exact embodiment herein shown and described.

Having thus described my invention, what I claim is:

1. In a rotary engine, the combination of two or more intermeshing and engaging rotors, shafts secured in said rotors and rotatably mounted in suitable bearings, each rotor having a plurality of right hand spirally disposed tooth blades extending from a plurality of circumferential points on said rotors located in a plane at right angles to the axis thereof toward one end of said rotors, and a plurality of left hand spirally disposed tooth blades extending from said plurality of circumferential points toward the opposite end of said rotors, said right and left hand tooth blades of each rotor meeting and joining and thereby forming angular pockets and a fluid inlet provided with a port for conducting fluid under pressure to said rotors, said port being so located and formed that said conducted fluid will be impinged within the angular pockets formed by said tooth blades.

2. In a rotary engine, the combination of two or more intermeshing and engaging rotors, shafts secured in said rotors and rotatably mounted in suitable bearings, each rotor having a plurality of right hand spirally disposed tooth blades extending from a plurality of circumferential points on said rotors located in a plane at right angles to the axis thereof toward one end of said rotors, and a plurality of left hand spirally disposed tooth blades extending from said plurality of circumferential points toward the opposite end of said rotors, said right hand and left hand spirally disposed tooth blades of one rotor meshing respectively with said left hand and right hand spirally disposed tooth blades of another rotor, whereby buckets are formed between the meshing tooth blades of said rotors, and a fluid inlet provided with a port

for conducting fluid under pressure to said rotors, said port being so located and formed that said conducted fluid will be impinged within the buckets formed by said tooth blades.

3. In a rotary engine the combination of two or more intermeshing and engaging rotors, shafts secured in said rotors and rotatably mounted in suitable bearings each rotor having a plurality of right hand spirally disposed tooth blades extending from a plurality of circumferential points on said rotors located in a plane at right angles to the axis thereof toward one end of said rotors and a plurality of left hand spirally disposed tooth blades extending from said plurality of circumferential points toward the opposite end of said rotors, said right and left hand tooth blades of each rotor meeting and joining and thereby forming angular pockets, and said right hand and left hand spirally disposed tooth blades of one rotor meshing respectively with said left hand and right hand spirally disposed tooth blades of another rotor, whereby buckets are formed between the meshing tooth blades of said rotors, and a fluid inlet provided with a port for conducting fluid under pressure to said rotors, said port being so located and formed that said conducted fluid will be impinged within the angular pockets formed by said tooth blades.

4. In a rotary engine the combination of two or more intermeshing and engaging rotors, shafts secured in said rotors and rotatably mounted in suitable bearings, each rotor having a plurality of right hand spirally disposed tooth blades extending from a plurality of circumferential points on said rotors located in a plane at right angles to the axis thereof toward one end of said rotors, and a plurality of left hand spirally disposed tooth blades extending from said plurality of circumferential points toward the opposite end of said rotors, said right and left hand tooth blades of each rotor meeting and joining and thereby forming angular pockets and a fluid inlet provided with a port having lateral passages leading into said pockets whereby the conducted fluid impacts in said pockets and against said tooth blades substantially in the direction of rotation of said rotors.

5. In a rotary engine the combination of two or more intermeshing and engaging rotors, shafts secured in said rotors and rotatably mounted in suitable bearings, each rotor having a plurality of right hand spirally disposed tooth blades extending from a plurality of circumferential points on said rotors located in a plane at right angles to the axis thereof toward one end of said rotors and a plurality of left hand spirally disposed tooth blades extending from said plurality of circumferential points

points toward the opposite end of said rotors, said right and left hand tooth blades of each rotor meeting and joining and thereby forming angular pockets, and a rib extending substantially parallel to the axes of said rotors and in contact with the peripheries of said rotors for at least a portion of their circumferences, said rib being provided with a port for conducting fluid under pressure to the said angular pockets of said rotors.

6. In a rotary engine the combination of two or more intermeshing and engaging rotors, shafts secured in said rotors and 15 rotatably mounted in suitable bearings, each rotor having a plurality of right hand spirally disposed tooth blades extending from a plurality of circumferential points on said rotors located in a plane at right 20 angles to the axis thereof toward one end of said rotors and a plurality of left hand spirally disposed tooth blades extending from said plurality of circumferential points toward the opposite end of said rotors, 25 said right and left hand tooth blades of each rotor meeting and joining and thereby forming angular pockets, and a rib extending substantially parallel to the axes of said rotors and in contact with the peripheries 30 of said rotors for at least a portion of their circumferences, said rib being provided with lateral passages leading into said pockets whereby the conducted fluid impacts in said 35 pockets and against said tooth blades substantially in the direction of rotation of said rotors.

7. In a rotary engine the combination of two or more intermeshing and engaging rotors, shafts secured in said rotors and 40 rotatably mounted in suitable bearings, each rotor having a plurality of right hand spirally disposed tooth blades extending from a plurality of circumferential points on said rotors located in a plane at right 45 angles to the axis thereof toward one end of said rotors and a plurality of left hand spirally disposed tooth blades extending from said plurality of circumferential points toward the opposite end of said rotors, said 50 right hand and left hand spirally disposed tooth blades of one rotor meshing respectively with said left hand and right hand spirally disposed tooth blades of another rotor, whereby buckets are formed between the meshing tooth blades of said rotors, and a rib extending substantially parallel to the axes of said rotors and in contact with the peripheries of said rotors for at least a portion of their circumferences, said rib being 55 provided with a port for conducting fluid under pressure to said buckets of said rotors.

8. In a rotary engine the combination of two or more intermeshing and engaging rotors, shafts mounted in said rotors and ro- 60

tatably mounted in suitable bearings, each rotor having a plurality of right hand spirally disposed tooth blades extending from a plurality of circumferential points on said rotors located in a plane at right angles to the axis thereof toward one end of said rotors and a plurality of left hand spirally disposed tooth blades extending from said plurality of circumferential points toward the opposite end of said rotors, said right hand and left hand spirally disposed tooth blades of one rotor meshing respectively with said left hand and right hand spirally disposed tooth blades of another rotor, whereby buckets are formed between the meshing tooth blades of said rotors, and a rib extending substantially parallel to the axes of said rotors and in contact with the peripheries of said rotors for at least a portion of their circumferences, said rib being provided with lateral passages leading into said buckets whereby the conducted fluid impacts in said buckets and against said tooth blades substantially in the direction of rotation of said rotors.

9. In a rotary engine the combination of two or more intermeshing and engaging rotors, shafts secured in said rotors and rotatably mounted in suitable bearings, each rotor having a plurality of right hand spirally disposed tooth blades extending from a plurality of circumferential points on said rotors located in a plane at right angles to the axis thereof toward one end of said rotors and a plurality of left hand spirally disposed tooth blades extending from said plurality of circumferential points toward the opposite end of said rotors, said right and left hand tooth blades of each rotor meeting and joining and thereby forming angular pockets, a rib extending substantially parallel to the axes of said rotors and in contact with the peripheries of said rotors for at least a portion of their circumferences, and one or more inlet ports located in said rib and opening into said intermeshing tooth blades substantially at the junction of said right and left hand spirally disposed tooth blades.

10. In a rotary engine the combination of two or more intermeshing and engaging rotors, shafts mounted in said rotors and rotatably mounted in suitable bearings, each rotor having a plurality of right hand spirally disposed tooth blades extending from a plurality of circumferential points on said rotors located in a plane at right angles to the axis thereof toward one end of said rotors and a plurality of left hand spirally disposed tooth blades extending from said plurality of circumferential points toward the opposite end of said rotors, said right hand and left hand spirally disposed tooth blades of one rotor meshing respectively with said left hand and right hand spirally disposed tooth blades of another rotor, whereby buckets are formed between the meshing tooth blades of said rotors, and a rib extending substantially parallel to the axes of said rotors and in contact with the peripheries of said rotors for at least a portion of their circumferences, said rib being provided with a port for conducting fluid under pressure to said buckets of said rotors.

disposed tooth blades of another rotor, whereby buckets are formed between the meshing tooth blades of said rotors, a rib extending substantially parallel to the axes

5 of said rotors and in contact with the peripheries of said rotors for at least a portion of their circumferences, and one or more inlet ports located in said rib and opening into said buckets at substantially the junction of said right and left hand spirally disposed tooth blades.

11. In a rotary engine the combination of two or more intermeshing and engaging

15 rotors, shafts secured in said rotors and rotatably mounted in suitable bearings, each rotor having a plurality of right hand spirally disposed tooth blades extending from a plurality of circumferential points on said

20 rotors located in a plane at right angles to the axis thereof toward one end of said rotors and a plurality of left hand spirally disposed tooth blades extending from said plurality of circumferential points toward the opposite end of said rotors, said right

25 and left hand tooth blades of each rotor meeting and joining and thereby forming angular pockets, a rib extending substantially parallel to the axes of said rotors and in contact with the peripheries of said rotors

30 for at least a portion of their circumferences, and one or more inlet ports located in said rib and opening into said intermeshing tooth blades at substantially the junction of

35 said right and left hand spirally disposed tooth blades, said ports being so arranged that the admission of the fluid under pressure into any pair of intermeshing tooth blades is cut off by the succeeding intermeshing tooth blades before the said first

40 mentioned tooth blades have developed their full capacity.

12. In a rotary engine the combination of two or more intermeshing and engaging

45 rotors, shafts secured in said rotors and rotatably mounted in suitable bearings, each rotor having a plurality of right hand spirally disposed tooth blades extending from a plurality of circumferential points on said

50 rotors located in a plane at right angles to the axis thereof toward one end of said rotors and a plurality of left hand spirally disposed tooth blades extending from said plurality of circumferential points to the

55 opposite end of said rotors, said right and left hand tooth blades of each rotor meeting and joining and thereby forming angular pockets, a rib extending substantially parallel to the axes of said rotors and in contact

60 with the peripheries of said rotors for at least a portion of their circumferences, and one or more inlet ports located in said rib and opening into said intermeshing tooth blades at substantially the junction of said

65 right and left hand spirally disposed tooth blades, said ports being so arranged in said

rib that a curve drawn parallel to said right or left hand tooth blades and tangent to the curve in which that port orifice which is the greatest distance from the formation of said pockets cut said rib, shall be shorter than the full length of either said right or said left hand tooth blades of each of said rotors, whereby the admission of the fluid under pressure into any pair of intermeshing tooth blades is cut off by the succeeding intermeshing tooth blades before the said first mentioned tooth blades have developed their full capacity.

13. In a rotary engine the combination of two or more intermeshing and engaging

70 rotors, shafts mounted in said rotors and rotatably mounted in suitable bearings, each rotor having a plurality of right hand spirally disposed tooth blades extending from a plurality of circumferential points on said

75 rotors located in a plane at right angles to the axis thereof toward one end of said rotors and a plurality of left hand spirally disposed tooth blades extending from said plurality of circumferential points to

80 the opposite end of said rotors, said right and left hand tooth blades of one rotor meshing respectively with said left hand and right hand spirally disposed tooth blades of another

85 rotor, whereby buckets are formed between the meshing tooth blades of said rotors, a rib extending substantially parallel to the axis of said rotors and in contact with the peripheries of said rotors for at least a portion of their circumferences, and one or more inlet ports located in said rib and opening into said buckets at substantially the

90 junction of said right and left hand spirally disposed tooth blades, said ports being so arranged that the admission of the fluid under pressure into any bucket is cut off by the tooth blades forming one side of the

95 succeeding bucket before the said first mentioned bucket has developed its full capacity.

14. In a reversible rotary engine the combination of two or more intermeshing and engaging rotors, shafts secured in said

100 rotors and rotatably mounted in suitable bearings, each rotor having three or more sections, each alternate section on each rotor being provided with a plurality of right hand spirally disposed tooth blades and the other alternate section of the same rotor being pro-

105 vided with a plurality of left hand spirally disposed tooth blades, the said right and left hand tooth blades on each rotor meeting and joining so as to form angular pockets.

15. In a reversible rotary engine the combination of two or more intermeshing and

115 engaging rotors, shafts secured in said rotors and rotatably mounted in suitable bearings, each rotor having three or more sections, each alternate section on each rotor being provided with a plurality of right

120

- hand spirally disposed tooth blades and the other alternate section of the same rotor being provided with a plurality of left hand spirally disposed tooth blades, the right hand and left hand tooth blades on one rotor meshing respectively with the left hand and right hand tooth blades of another rotor, whereby buckets are formed between the meshing tooth blades of the said rotors.
16. In a reversible rotary engine the combination of two or more intermeshing and engaging rotors, shafts secured in said rotors and rotatably mounted in suitable bearings, each rotor having three or more sections, each alternate section on each rotor being provided with a plurality of right hand spirally disposed tooth blades and the other alternate section of the same rotor being provided with a plurality of left hand spirally disposed tooth blades, the said right and left hand tooth blades on each rotor meeting and joining so as to form angular pockets, the right hand and left hand tooth blades on one rotor meshing respectively with the left hand and right hand tooth blades of another rotor, whereby buckets are formed between the meshing tooth blades of the said rotors.
17. In a reversible rotary engine the combination of two or more intermeshing and engaging rotors, shafts secured in said rotors and rotatably mounted in suitable bearings, each rotor having three or more sections, each alternate section on each rotor being provided with a plurality of right hand spirally disposed tooth blades and the other alternate section of the same rotor being provided with a plurality of left hand spirally disposed tooth blades, the said right and left hand tooth blades on each rotor meeting and joining so as to form angular pockets, a rib extending across said angular pockets on one side of said rotors and a rib extending across said angular pockets on the opposite side of said rotors, each of said ribs being substantially parallel to the axes of said rotors and in contact with the peripheries of said rotors for at least a portion of their circumferences.
18. In a reversible rotary engine the combination of two or more intermeshing and engaging rotors, shafts secured in said rotors and rotatably mounted in suitable bearings, each rotor having three or more sections, each alternate section on each rotor being provided with a plurality of right hand spirally disposed tooth blades and the other alternate section of the same rotor being provided with a plurality of left hand spirally disposed tooth blades, the right and left hand tooth blades on one rotor meshing respectively with the left hand and right hand tooth blades of another rotor, whereby buckets are formed between the meshing tooth blades of the said rotors, a rib extend-

ing across said buckets on one side of said rotors and a rib extending across said buckets on the opposite side of said rotors, each of said ribs being substantially parallel to the axes of said rotors and in contact with the peripheries of said rotors for at least a portion of their circumferences.

19. In a reversible rotary engine the combination of two or more intermeshing and engaging rotors, shafts secured in said rotors and rotatably mounted in suitable bearings, each rotor having three or more sections, each alternate section on each rotor being provided with a plurality of right hand spirally disposed tooth blades and the other alternate section of the same rotor being provided with a plurality of left hand spirally disposed tooth blades, the said right and left hand tooth blades on each rotor meeting and joining so as to form angular pockets, a rib extending across said angular pockets on one side of said rotors and a rib extending across said angular pockets on the opposite side of said rotors, each of said ribs being substantially parallel to the axes of said rotors and in contact with the peripheries of said rotors for at least a portion of their circumferences, and one or more inlet ports located in each of said ribs and openings into the intermeshing tooth blades at substantially the junction of each right hand and left hand set of tooth blades where the said angular pockets are formed.

20. In a reversible rotary engine the combination of two or more intermeshing and engaging rotors, shafts secured in said rotors and rotatably mounted in suitable bearings, each rotor having three or more sections, each alternate section on each rotor being provided with a plurality of right hand spirally disposed tooth blades and the other alternate section of the same rotor being provided with a plurality of left hand spirally disposed tooth blades, the right and left hand tooth blades on one rotor meshing respectively with the left hand and right hand tooth blades of another rotor, whereby buckets are formed between the meshing tooth blades of the said rotors, a rib extending across said buckets on one side of said rotors, a rib extending across said buckets on the opposite side of said rotors, each of said ribs being substantially parallel to the axes of said rotors and in contact with the peripheries of said rotors for at least a portion of their circumferences, and one or more inlet ports located in each of said ribs and opening into said buckets.

21. In a reversible rotary engine the combination of two or more intermeshing and engaging rotors, shafts secured in said rotors and rotatably mounted in suitable bearings, each rotor having three or more sections, each alternate section on each rotor being provided with a plurality of right hand

hand spirally disposed tooth blades and the other alternate section of the same rotor being provided with a plurality of left hand spirally disposed tooth blades, the said right 5 and left hand tooth blades on each rotor meeting and joining so as to form angular pockets, a rib extending across said angular pockets on one side of said rotors and a rib extending across said angular pockets 10 on the opposite side of said rotors, each of said ribs being substantially parallel to the axes of said rotors and in contact with the peripheries of said rotors for at least a portion of their circumferences, and one or more 15 inlet ports located in each of said ribs and openings into the intermeshing tooth blades at substantially the junction of each right hand and left hand set of tooth blades where the said angular pockets are formed, said 20 ports being so arranged that the admission of the fluid under pressure into any pair of intermeshing tooth blades is cut off by the succeeding intermeshing tooth blades before the said first mentioned tooth blades have 25 developed their full capacity.

22. In a reversible rotary engine the combination of two or more intermeshing and engaging rotors, shafts secured in said rotors and rotatably mounted in suitable bearings, each rotor having three or more sections, each alternate section on each rotor

being provided with a plurality of right hand spirally disposed tooth blades and the other alternate section of the same rotor being provided with a plurality of left hand spirally disposed tooth blades, the right and left hand tooth blades on one rotor meshing respectively with the left hand and right hand tooth blades of another rotor, whereby buckets are formed between the meshing 35 tooth blades of the said rotors, a rib extending across said buckets on one side of said rotors, a rib extending across said buckets on the opposite side of said rotors, each of said ribs being substantially parallel to the 40 axes of said rotors and in contact with the peripheries of said rotors for at least a portion of their circumferences, and one or more inlet ports located in each of said ribs and opening into said buckets, said ports 45 being so arranged that the admission of the fluid under pressure into any bucket is cut off by the tooth blades forming one side of the succeeding bucket before the said first mentioned bucket has developed its full capacity. 50

In witness whereof, I have hereunto set my hand in the presence of two witnesses.

JOHN H. VAN DEVENTER.
